W P. JENNINGS.

MITT

No. 14,580

January 29, 1884.

UNITED STATES PATENT OFFICE.

WARREN P. JENNINGS, OF BROOKLYN, NEW YORK.

DESIGN FOR A MITT.

SPECIFICATION forming part of Design No. 14,580, dated January 29, 1884.

Application filed November 26, 1883. Term of patent 7 years.

To all whom it may concern:

Be it known that I, WARREN P. JENNINGS, a resident of Brooklyn, in the county of Kings and State of New York, have invented and produced a new and original Design for Ladies' Mitts, of which the following is a full description, in connection with the accompanying photograph, which represents a face view of my new design for a mitt.

This invention relates to a new design for ladies' mitts; and it consists in the arrangement of apertures that form figures for ornamenting the mitt, as hereinafter more fully described.

At the upper end the mitt A has an ornamental band, which is composed of stripes *a* and intervening rows of hexagons *b*, as shown. Below this is another pair of stripes, *c*, and a row of hexagons, *d*, between them. Below this there are series of stripes *e e*. The central part

of the mitt is decorated by stripes *f*, which have between them a stripe, *g*, of quite narrow hexagons. The lower part of the mitt is decorated by stripes *h*, containing a row of hexagons, *i*, between them.

25 I claim—

1. The design for a mitt, the same consisting of the figures *a*, *b*, *c*, and *d*, substantially as shown.

2. The design for a mitt, the same consisting 30 of the figures *a*, *b*, *c*, *d*, *e*, *f*, and *g*, substantially as shown.

3. The design for a mitt, the same consisting of the figures *a*, *b*, *c*, *d*, *e*, *f*, *g*, *h*, and *i*, substantially as shown.

WARREN P. JENNINGS.
